[57] CLAIM

The ornamental design for a clamp, as shown and described.

DESCRIPTION

FIG. 1 is a front elevational view of a clamp showing my new design, the rear being a mirror image thereof;
FIG. 2 is a side elevational view taken from the right of FIG. 1;

FIG. 3 is a top plan view, the bottom being a mirror image thereof;

FIG. 4 is a sectional view taken in the direction of the arrows on line IV—IV of FIG. 1.

FIG.1

FIG.2
